UNITED STATES PATENT OFFICE

FRIEDRICH KARL TEICHGRÄBER, OF BERLIN-SCHMARGENDORF, GERMANY

ELECTROMAGNETIC DRIVING DIRECTION INDICATOR

Application filed March 14, 1929, Serial No. 346,912, and in Germany March 26, 1928.

Electro-magnetic driving direction indicators can be divided into two main types, that is, the so-called drum indicators in which a disc is rotated by means of an electro-magnetic yoke, so that the driving direction may be indicated by the position of said disc; and the so-called "Winkers" angle arm indicators in which an indicator arm is moved by the electro-magnet from its normal vertical position into an upright indicating position. The last mentioned type of indicator possesses the advantage that when the angle arm is in the indicating position the contour of the instrument is altered, so that it is more clearly visible, and consequently complies with many official regulations for public traffic vehicles that only such indicators are to be used.

The present invention relates to such an angle indicator. In the hitherto known forms of construction there is always a firm connection, arranged directly or indirectly, between the angle arm and the magnet core actuated by the solenoid. As however in order to avoid having a dead point, the axis of the point of attachment cannot lie in a vertical plane with the axis of rotation of the angle arm, but must be shifted a little to one side, the magnet core describing a double curve. This necessitates the use of an oscillating coil, or one of special construction. The first mentioned form of construction takes up a comparatively large amount of room, and also necessitates movable wire connections, whilst the last mentioned form is comparatively expensive in construction. Furthermore all these movable connections and arrangements are uncertain in action, as by inappreciable alterations in the shape, or by the collection of dirt thereon, resistances are created, which the battery, always giving only a small current, is unable to overcome.

A further defect of these angle arms consists in the fact that they are easily moved out of the normal vertical position by the vibration of the vehicle and in this way also give rise to uncertain action or faulty indication. This defect can only be remedied by springs or control magnets in a complicated

manner and even then the defect could not be surmounted with certainty.

The present invention overcomes all these defects, whilst at the same time simplifying the construction of the part controlling the angle arm. The main characteristic of the invention consists in that the actuating slot through which the magnet core engages the angle arm, is provided with a cut-out part which rests on the actuating pin of the arm in the normal position of the angle arm, so that the weight of the magnet core holds the angle arm in the normal position, and in the simplest possible manner.

The accompanying drawing shows as an example a form of construction of such an arrangement in a driving direction indicator in Fig. 1 in the normal position and in Fig. 2 in the working position.

The angle arm top *a* is provided with a simple or hook shaped stud, or so-called carrying pin *b*, whose curving movement is taken up by the slot *c* of the free magnet core *d* freely moving without any point of attachment in the magnet coil *s*. A cut-out part *i* surrounds the pin *b* of the indicator arm at its drop into the normal position, and retains it in this position until current is switched on and raises the magnet core up from the pin. In order to reduce friction a friction roller can be fitted on the pin *b*. The casing *g* surrounds the arrangement.

Having now particularly described and ascertained the nature of my said invention and in what manner the same is to be performed, I declare that what I claim is:

1. An electromagnetic driving direction indicator comprising a movable pivoted indicator arm having a projection offset from the pivot, a core arranged above said arm and having an open slot to receive said projection, said core fitting snugly in the coil of a solenoid the upper wall of said slot comprising a seat adapted to cooperate with said projection and to support the core upon said projection, whereby to maintain the arm in its downward position by the weight of the core.

2. In an electromagnetic driving direction indicator comprising a pivoted indicator arm having a projecting pin in proximity to and

spaced from the point where the arm is pivoted, a core arranged above said arm and having a slot receiving said pin, said core fitting snugly in the coil of a solenoid, and a seat defining part of the slot adapted to cooperate with the pin and support the core upon the pin, whereby to maintain the arm in one position by the weight of the core.

In testimony that I claim the foregoing as
10 my invention, I have signed my name hereto.

FRIEDRICH KARL TEICHGRÄBER.
